RECIPROCABLE GUIDE STRUCTURE WITH SELF-ADJUSTING ROCKER SHOES

John R. Sibley, Franklin, Pa., assignor to Joy Manufacturing Company, Pittsburgh, Pa., a corporation of Pennsylvania.

Original application July 5, 1949, Serial No. 102,996. Divided and this application June 20, 1955, Serial No. 516,594.

6 Claims. (Cl. 308—3)

This invention relates to a continuous mining apparatus and more particularly to a guiding structure for the vein-attacking and disintegrating mechanism of such an apparatus for guiding the same during its back and forth rectilinear movements.

In a continuous miner of the kind disclosed in my copending application Serial No. 102,996, filed July 5, 1949, which is a continuation-in-part of a copending application Serial No. 47,422, filed September 2, 1948, now abandoned, and has matured into Patent No. 2,798,713, dated July 9, 1957, the vein-attacking and disintegrating mechanism for dislodging and disintegrating the mineral of a solid mine vein is mounted for back and forth rectilinear movements relative to the frame structure on which the mechanism is mounted. The present invention resides in the improved guiding means for guiding the attacking and disintegrating mechanism during such rectilinear movements.

In a preferred embodiment, the invention may comprise rectilinearly movable members and guiding means therefor including cooperating rocker shoe and bearing elements, certain ones of which may have concave sockets for receiving coating convex elements whereby there may be relative rocking of the parts during guiding to prevent undue binding. Such cooperating elements, as disclosed, may assume the form of rocker shoes having plane guiding surfaces and convex bearing surfaces fitted in concave sockets in bearing supports.

An object of the present invention is to provide improved guiding means for the attacking and disintegrating mechanism of a continuous mining apparatus. Another object is to provide an improved guide structure embodying self-adjusting rocker shoes whereby binding of the guides during adjustment is substantially avoided. Yet another object is to provide an improved horizontal guiding means for a rectilinearly movable frame. These and other objects and advantages of the invention will, however, hereinafter more fully appear.

This application is a division of my copending application Serial No. 102,996, filed July 5, 1949.

In the accompanying drawings there is shown for purposes of illustration one form which the invention may assume in practice.

In these drawings:

Fig. 1 is a horizontal sectional view taken through a portion of a continuous mining apparatus, showing details of the improved guide structure.

Fig. 2 is a view in longitudinal vertical section taken on the plane of line 2—2 of Fig. 1.

Fig. 3 is a cross sectional view taken on line 3—3 of Fig. 2.

Fig. 4 is a detail longitudinal vertical sectional view taken on line 4—4 of Fig. 3, illustrating a portion of the guiding means for the sliding frame.

Figs. 5, 6 and 7 are detail vertical sectional views taken respectively on lines 5—5, 6—6 and 7—7 of Fig. 4, showing details of the guiding means.

The continuous mining apparatus in which the present

2

invention is embodied may generally comprise a base 1 having a frame 2 which has swiveled thereon, at 3, to swing about an upright axis in horizontal planes with respect thereto, a horizontal supporting frame or turntable 4. The swiveled supporting frame or turntable has a horizontal portion 5 projecting forwardly in advance of the base, and guided on this horizontal frame portion for movement rectilinearly relative thereto in a radial direction relative to the swivel axis is a sliding frame or support 6 on which a swingable frame or bar structure 7 of a vein-attacking and disintegrating mechanism, generally designated 8, is pivotally mounted to swing in vertical planes for dislodging and disintegrating the mineral of a solid mine vein. The attacking and disintegrating mechanism comprises a series of endless disintegrating chains 9 guided for circulation in parallel vertical orbits along guideways on the swingable frame structure 7 and motors 10 carried by the swiveled frame 5 drive through extensible universal drive shafts 11, reduction gearings 12 enclosed within housings 13 carried at the opposite sides of the sliding support 6. These reduction gearings drive a transverse shaft 14 arranged coaxially with the frame pivot, and driving sprockets 15 secured to the shaft, in turn, engage and drive the series of endless disintegrating chains. Thus, the motors 10 may drive the disintegrating chains irrespective of the rectilinearly adjusted position of the sliding frame 6.

The horizontal forward portion 5 of the swiveled supporting frame 4 has laterally spaced, parallel, upright side portions 17 formed integral with a horizontal frame portion 18, and the motors 10 are secured to the outer sides of these side frame portions, as shown in Figs. 1 and 3. The side frame portions 17 have extending longitudinally along the inner sides thereof horizontal guideways 19 which receive lateral guides 20 on the sliding frame or support 6. The forward ends of the side portions 17 carry bearing supporting blocks 21, secured thereto as by screws, and these blocks have concave recesses 22 in which self-adjusting guide members in the form of bearing segments or rockers 23 of semicircular cross sectional shape are seated, and the plane bottom surfaces of the forward portions of the guides 20 are slidably supported by these bearing segments or rockers, as shown in Fig. 4. Evidently, if desired, the parts may be reversed with the semicircular guide or bearing members 23 providing bearing supports on which the blocks 21 are mounted as rockers with the upper surfaces of the blocks then engaging the plane bottom surfaces of the guides. Similar upper bearing segments 24 are seated in concave recesses 25 of the upper portion of the guideways and are slidably engaged by the plane upper surface of the guides 20. The upper segments 24 are wedge-shaped, as shown in Fig. 6, and may be adjusted by screws 26 to take up any play. Wear inserts 27 of disc shape carried by the rearward portions of the guides slidably engage the plane bottom sliding surface of the guideways, as shown in Fig. 5. Replaceable wear plates 28 are arranged between the upper surface of the rear guide portion and the upper surface of the guideway and extend downwardly along the inner edges of the guides.

Suitable fluid operated means is provided for reciprocating the sliding frame or support along its guideways, and for this purpose there is illustrated an arrangement which includes double-acting fluid cylinders 29 arranged longitudinally along the inner sides of the parallel side frame portions 17 of the swiveled supporting frame or turntable 4. These fluid cylinders are pivotally mounted, at 30, at their rear ends on the swiveled frame and contain reciprocable pistons 31 having piston rods 32 extending forwardly from the front cylinder heads. The front ends of the piston rods are pivotally connected, at

33, to the sliding frame or support 6. When fluid under pressure is supplied to one end or the other of the cylinders 29, the pistons may be moved to feed the sliding frame 6 rectilinearly back and forth along the guideways 19. By trapping fluid in the cylinders, the pistons may be locked in position to hold the sliding frame against sliding movement. This structure, together with the means for supplying fluid under pressure to the cylinders, is fully disclosed in the copending application above referred to.

As a result of this invention, an improved guiding structure is provided for the rectilinearly movable attacking and disintegrating mechanism of a continuous mining apparatus. By the provision of the improved sliding guides, together with the coacting rocker shoe structure, guiding is effected in an improved manner while undue binding of the parts is substantially avoided. The structure is not only effective in operation but is simple and rugged in design, well adapted for its intended purpose. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a reciprocable horizontal member having a bottom plane guide surface, a guide member for guiding said first member during its reciprocation and having an upper plane bearing surface with which said guide surface has sliding engagement, and means relative to which said horizontal member is reciprocable for mounting said guide member for limited rocking movement about a relatively stationary transverse axis at right angles to a line extending in the direction of reciprocation of said first member.

2. A combination as set forth in claim 1 wherein said mounting means for said guide member provides a curved bearing surface of relatively large area lying in the surface of a cylinder.

3. A combination as set forth in claim 1 wherein said mounting means for said guide member provides a

curved bearing surface of relatively wide area lying in the surface of a cylinder and said guide member has a complementary curved surface opposed to said plane bearing surface and bearing against said curved bearing surface.

4. In combination, a reciprocable member having a plane guide surface, a supporting frame providing a guideway for receiving said reciprocable member, and means for taking up any excessive play of said reciprocable member in its guideway comprising a transversely disposed wedge having adjusting means, said wedge movable axially in a direction at right angles to a line extending in the direction of reciprocation of said member, said wedge having a curved surface lying in the surface of a cone and engaging a complementary curved surface whereby said wedge member may rock slightly about said transverse axis.

5. In combination, a supporting frame providing a horizontal guideway, a reciprocable member mounted in said guideway and having a bottom plane guide surface, a guide segment for guiding said member during its reciprocation and having an upwardly facing plane surface with which said bottom guide surface has sliding engagement, said reciprocable member movable along its path of reciprocation into a position wherein its outer portion substantially overhangs said supporting frame, and relatively stationary means near the outer end of said guideway for mounting said guide segment for limited rocking movement about a relatively stationary transverse axis at right angles to a line extending in the direction of reciprocation of said reciprocable member.

6. A combination as set forth in claim 5 wherein said mounting means for said guide segment provides a curved bearing surface of relatively wide area lying in the surface of a cylinder, said guide segment having a complementary curved surface bearing against said curved bearing surface.
